[57] CLAIM

The ornamental design for an air deflector for refrigerated vehicles, substantially as shown.

DESCRIPTION

FIG. 1 is a front elevational view of an air deflector for refrigerated vehicles embodying our new design;

FIG. 2 is a top plan view thereof;

FIG. 3 is a bottom plan view thereof;

FIG. 4 is a side elevational view thereof taken from the left side of FIG. 1; and

FIG. 5 is a side elevational view thereof taken from the right side of FIG. 1.

*FIG. 1.**FIG. 2.**FIG. 3.**FIG. 4.**FIG. 5.*
